UNITED STATES PATENT OFFICE.

ALFRED H. DONAHOE, OF CHICAGO, ILLINOIS, ASSIGNOR TO ASSOCIATED ENGINEERS COMPANY, OF CHICAGO, ILLINOIS.

TEST SYSTEM.

1,209,407.

Specification of Letters Patent. Patented Dec. 19, 1916.

Application filed October 16, 1915. Serial No. 56,228.

To all whom it may concern:

Be it known that I, ALFRED H. DONAHOE, a citizen of the United States, residing at Chicago, in the county of Cook and State 5 of Illinois, have invented a certain new and use useful Improvement in Test Systems, of which the following is a full, clear, concise, and exact description, reference being had to the accompanying drawings, forming a 10 part of this specification.

My invention relates to signaling systems and is of particular utility in connection with central station work where it can, for instance, be utilized to properly give answer 15 back signals as to the condition of remotely controlled apparatus.

My invention further contemplates the provision of an improved style of signal in which dangers of short circuit or improper 20 actuation are avoided, thus to insure absolute reliance upon the indications which the system is designed to give.

In one form of carrying out the invention, and which is the one selected for illustration 25 herein, the system is applied to the control of an oil switch, for instance, which is remotely controlled, and in which suitable automatically stopped motor mechanism is utilized to move the switch from one position 30 to its alternative position. At the point of control remote for the switch, I provide a pair of signals so arranged that an answer back signal is given to indicate after the operation of the switch that such operation 35 has been completed, and that the switch is ready for an alternative movement, if desired. The signals may also be used to continuously indicate the condition of the switch, that is, the position it occupies.

40 My present invention relates, as stated, to the style of signal and the arrangement of the system.

I will explain this particular form of use 45 of my invention in connection with the accompanying drawing, in which—

Figure 1 is a diagrammatic circuit arrangement of the system constructed in accordance with my invention and using my improved signal; Fig. 2 is a front view of 50 a panel section of a switchboard structure showing the manner of mounting; Fig. 3 is a rear view thereof, and Fig. 4 is a side view of my improved signal.

The system in which my invention finds 55 particular use is shown diagrammatically in

Fig. 1, when it is desired to operate, for instance, a remotely controlled oil switch having the operating coils 1 and 2, which operating coils receive their current from a direct current local station circuit consisting 60 of the conductors 3 and 4. This local circuit which is supplied by the generator 5 is not the outgoing power circuit of the generator station, but is merely the local direct current source of power utilized for 65 operating auxiliary apparatus in the generator station itself. Whenever the oil switch moves from one position to another it moves the contact element 6 from the position shown in Fig. 1 where it connects together 70 the contacts 7 and 8 to its alternative position where it connects together the contacts 9 and 10. The coils 1 and 2 of course are merely starting coils to start the motor, which automatically stops itself when its 75 movement is completed as readily understood in the art, all as apparent from the dotted indication of such a switch shown in Fig. 1.

My improved switch board panel 11 which 80 is at the point of control has mounted upon it a switch consisting of the switch lever 12 which is adapted to contact either with the contact 13 or the contact 14 as the case may be. The switchboard panel is also provided 85 with two of my improved lamps or signals 15, 16, which have the construction more clearly shown in Fig. 4, and which are held in place upon the mounting clips 17. The panel is also provided at its rear with three 90 resistance elements 18, 19 and 20 as illustrated in Figs. 1 to 3.

Tracing now the circuit conditions, it will be seen that the switch arms 12 are connected directly to the main 3. The main 3 extends 95 by means of the conductor 21 to a terminal of the resistances 18. From the other terminal 22 of this resistance 18 the connection extends to one terminal of lamp 15, and also to one terminal of the lamp 16. The remaining terminal of the lamp 15 then extends conductively through the resistance 20 to the contact 13, and the remaining terminal of the lamp 16 extends conductively through the resistance 19, to the terminal 14. The 100 terminals 13 and 14 then are connected by means of conductors 23 and 24 to terminals of the starting coils 1 and 2. The remaining terminals of the starting coils 1 and 2 then are connected respectively to the contact 110

points 7 and 9. The contact points 8 and 10 are connected together, and are connected by means of the conductor 25 to the main 4.

Assuming that the parts now are in the 5 position shown in Fig. 1, then a circuit is established which can be traced from the main 4, by way of conductor 25, through contacts 8 and 7, coil 1, resistance 19, lamp 16, resistance 18, conductor 21, to the main 3. 10 The inclusion in this circuit of the lamp 16 and the resistances 18 and 19 prevents the coil 1 from being operatively energized. Now should it be desired to energize this coil, then the switch arm 12 is moved from 15 the position it occupies into engagement with the contact 14 and the circuit through the coil 1 may then be traced from the main 4, by way of conductor 25, through contacts 8 and 7, coil 1, contact 14, switch arm 12, and 20 conductor 26 to the main 3. The lamp 16 and coils 18 and 19 are thus short circuited and the coil 1 is operatively energized to move the oil switch to its alternative position. At the same time the contact element 25 moves into engagement with the contacts 9 and 10 which indicates by the ignition of the lamp 15 that the operation of moving 25 the oil switch to its alternative position has been completed, and that the switch is in 30 condition to be operated back to its original position if desired. The lamp 15 will now be in circuit similarly as the lamp 16 was in circuit heretofore.

My improved signal as shown consists of 35 the glass shell 27 which is capped by the copper heads 28, 28, to which copper heads the filament 29 is of course soldered or otherwise suitably electrically connected. This filament 29 is wavy as shown so that 40 the signal answers as a daylight signal, in that the lineal reflection which is frequently obtained from the tubes through sunlight will not be mistaken for a glowing filament. The glass shells are preferably made of 45 green and red coloration so as to be readily distinguishable. This improved signal, as will be seen, does not include a looped filament, which filament when breaking or otherwise, or due to the contacts in the 50 socket becomes short circuited, thus being liable to cause serious accidents in the operation of remotely controlled apparatus. It will be seen that the breakage of this filament cannot cause a short circuit, nor can 55 there be a short circuit in the lamp base, as there is no lamp base, strictly speaking, the terminal springs having been mounted apart to accommodate the lamp.

It will be understood of course that the 60 short circuiting of the resistances included in series with the coil 1 under the conditions shown would cause an operation of that coil, and this short circuiting of the resistance or signal is prevented by the use of the particu- 65 lar style of filament and lamp referred to.

There can be no short circuiting through the signals 15 or 16, although there may of course be an open circuit, but that would not cause an actuation of the remote oil switch. The type of lamp used permits location on 70 the front of the switchboard, which obviates the necessity of large openings in the switchboard for the insertion of bull's-eye signal lights. Visibility is also greatly increased. Bull's-eye signals are very misleading in 75 daylight which may be due to sunlight behind the switchboard, or even sunlight shining directly on the switchboard, or any other reflected light would accomplish the same result. The general arrangement of this 80 system greatly increases the factor of safety. The location of the signals on the front of the board increases accessibility which is very important with inclosed types of control boards, such as bench boards. A single 85 unitary structure can also be provided as shown, thus greatly increasing the simplicity.

From what has been described it is thought the nature of my invention will be readily clear to those skilled in the art, and 90 that my invention is susceptible of many modifications.

Having however thus described one form 95 of my invention, what I claim as new and desire to secure by Letters Patent is:

1. A signaling system of the character described comprising a translating device, remotely located circuit controlling means for controlling the selective operation of 100 said translating device, switching mechanism at said translating device and operable into its alternative positions in accordance with the actuations of said translating device, for controlling the character of actuation of said translating device, a plurality 105 of signals in proximity to said circuit controlling means and selectively controlled by said circuit controlling means and said switching mechanism, resistances for said signals, and a panel board upon which said 110 signals, resistances, and circuit controlling means are mounted, said signals and circuit controlling means being mounted on the front face of said panel board, and said resistances being mounted rearwardly of 115 said panel board.

2. A signaling system of the character described comprising a translating device, remotely located circuit controlling means for controlling the selective operation of 120 said translating device, switching mechanism at said translating device and operable into its alternative positions in accordance 125 with the actuations of said translating device, for controlling the character of actuation of said translating device, a plurality of signals in proximity to said circuit controlling means and selectively controlled by said circuit controlling means and said switching mechanism, said circuit control- 130

ling means and said switching mechanism controlling said signals over common circuits, resistances for said signals, and a panel board upon which said signals, resistances, and circuit controlling means are mounted, said signals and circuit controlling means being mounted on the front face of said panel board, and said resistances being mounted rearwardly of said panel board.

3. A signaling system of the character described comprising a translating device, remotely located circuit controlling means for controlling the selective operation of said translating device, switching mechanism at said translating device and operable into its alternative positions in accordance with the actuations of said translating device, for controlling the character of actuation of said translating device, a plurality of signals in proximity to said circuit controlling means and selectively controlled by said circuit controlling means and said switching mechanism, said circuit controlling means when actuated into one or the other of its positions serving to short circuit one or the other of said signals, resistances for said signals, and a panel board upon which said signals, resistances, and circuit controlling means are mounted, said signals and circuit controlling means being mounted on the front face of said panel board, and said resistances being mounted rearwardly of said panel board.

4. A signaling system of the character described comprising a translating device, remotely located circuit controlling means for controlling the selective operation of said translating device, switching mechanism at said translating device and operable into its alternative positions in accordance with the actuations of said translating device, for controlling the character of actuation of said translating device, a plurality of signals in proximity to said circuit controlling means and selectively controlled by said circuit controlling means and said switching mechanism, said circuit controlling means and said switching mechanism controlling said signals over common circuits, said circuit controlling means when actuated into one or the other of its positions serving to short circuit one or the other of said signals, resistances for said signals, and a panel board upon which said signals, resistances, and circuit controlling means are mounted, said signals and circuit controlling means being mounted on the front face of said panel board, and said resistances being mounted rearwardly of said panel board.

In witness whereof I hereunto subscribe my name this 8th day of October, A. D. 1915.

ALFRED H. DONAHOE.
